UNITED STATES PATENT OFFICE.

WILLIAM JANDUS, OF CLEVELAND, OHIO.

ELECTROMETRIC APPLIANCE.

1,107,670.

Specification of Letters Patent. Patented Aug. 18, 1914.

Application filed April 16, 1906. Serial No. 311,853.

To all whom it may concern:

Be it known that I, WILLIAM JANDUS, a citizen of the United States, resident of Cleveland, county of Cuyahoga, and State of Ohio, have invented a new and useful Improvement in Electrometric Appliances, of which the following is a specification, the principle of the invention being herein explained and the best mode in which I have 5 contemplated applying that principle, so as to distinguish it from other inventions.

My invention relates to means for converting large units of electrical energy into mechanical movement by means of the principle of the expansion and contraction of electric conductors resulting from the heat generated by their resistance to the flow of an electric current, and particularly to means for thus converting electrical energy 15 in its application to electro-metric appliances.

The object of the invention is to utilize without waste of external resistance the full value of the current passing through the 20 operating elements and thereby to permit of a larger scope of torque in such instruments while reducing the heat and frictional factors to a negligible quantity. This object is attained by stringing the full length 25 of the resistance to be used, on suitably insulated supports, so as to produce an electro-thermic element comprising a plurality of strands of very fine wire. In this manner great lengths of wire may be wound into 30 neat, compact, flat coils occupying a very small compass, and by suitable mechanism the full value of the expansion and contraction 35 of the electro-thermic element thus formed may be converted into movement by 40 multiplying devices. A distinctive feature of these elements is that they are readily detachable and replaceable, and complete within themselves as an article of manufacture. Furthermore, the insulating supports of the 45 elements are so designed that, when placed in operating position, the elements are self-adjusting as to the tension of the individual strands of wire, that is, the individual wires act at substantially the same tension, and 50 also simultaneously and collectively.

By the use of an electro-thermic element of the above-described construction and properties,—the specific parts of which and their relative arrangement will be herein- 55 after fully described,—I am enabled to obtain from twice to one-hundred or more

times the torque effect of the single-wire instruments of the prevailing type, and I have thus a large margin for reducing the heat and tension factors of the present hot-wire 60 devices.

Said invention as embodied in a voltmeter, and, also, one form of construction which is capable of embodiment in an ammeter, are hereinafter fully described and 65 specifically set forth in the claims.

The annexed drawings and the following description set forth in detail certain mechanism embodying the invention, said disclosed means constituting but one of various 70 mechanical forms in which the principle of the invention may be used.

In said annexed drawings: Figure 1 represents a plan view of a volt-meter embodying my invention, the cover-plate being removed, and an annular member, which supports the indicating needle and some connected parts, being broken away to disclose the electro-thermic element, a thermic element, and other parts of the invention connected therewith; Fig. 2 represents an elevation of the invention, with part of the lower case, and the supporting member for the indicating needle broken away and in section; Figs. 3 and 4 represent elevations of 80 the right-hand and left-hand ends, respectively, of the invention; Figs. 5 and 6 represent elevations respectively, of a spring-plate and a second plate adapted to oscillate upon pin-bearings provided upon said 85 spring-plate; Fig. 7 represents an edge view of said oscillatory plate; Fig. 8 represents an elevation of a pivoted frame secured to each end of the electro-thermic element, the bearing-pins of the especial frame here 90 shown being so disposed as to adapt this frame to be secured to the left-hand end of the element which I have illustrated; Fig. 9 represents an enlarged broken perspective view of said electro-thermic element with the 95 locking device or frame, shown in Fig. 8 removed; Figs. 10 and 11 represent edge and face views, respectively, of said element, showing the pivoted frames in position; Figs. 12 and 13 represent views of an elec- 100 tro-thermic element as modified for use in an ammeter; Figs. 14 and 15 represent views of an element which I employ as a compensatory thermic element, and Figs. 16 and 17 are respectively a transverse and a longi- 105 tudinal section of one of the supports forming a part of the electro-thermic element.

The electro-thermic elements, each of which is entire as a new article of manufacture, constitute the important feature of my invention, and one of them is used in each machine or appliance. I shall now describe the construction of the same as embodied in a volt-meter, particular reference being made to Figs. 9, 10, and 11, in which said element is shown. I have designated the same by the reference character A, and it 10 comprises a continuous conductor of fine metal wire of high electrical resistance, wound over and over two insulating sheaths $a' a'$, covering suitable cores or supports a^9 , thus forming a flat coil comprising a plurality of wires a . These sheaths $a' a'$ form in effect a part of the cores or supports and are provided with deep grooves a^{10} , in which the wire is sunk, as shown in Fig. 9. 15 The supports a^9 can best be described as comprising two parts of a divided bobbin of small diameter, since they are in effect the two halves of what would be a single bobbin if the opposing surfaces of said supports 20 were brought into juxtaposition. In other words, both supports could be derived from a single bobbin, comprising two side portions of circular cross-section and an intermediate thin portion of rectangular cross- 25 section, by cutting said bobbin apart longitudinally of said thin portion. The grooves a^{10} , as will be clearly noted in Fig. 9, run transversely of the axial line of the supports a^9 and extend throughout the whole width 30 of said supports. The hot-wire or electro-thermic element ultimately reduced comprises a plurality of wires and the two parts of the grooved insulating divided bobbin or grooved insulating supports. The wires a 35 are sunk into the grooves a^{10} of these bobbin parts $a^9 a^9$ so that they are on a level with, or below the level of, the outer surface of said sheaths $a' a'$, and cannot be crushed, but are free to move and yet are thus per- 40 manently secured to said sheaths $a' a'$. Thus the wires can pull upon the supports individually and can adjust themselves individually relatively to said supports, which adjustment tends to equalize the tension 45 upon such wires. The divided bobbin parts a^9 and sheaths $a' a'$ are supplemented by outer insulating sheaths a^2 which inclose said sheaths $a' a'$, and thus, in combination with the latter, form effectual insulating 50 coverings for the wires a by means of which the latter are isolated one from the other. Incasing the sheaths a^2 transversely of the wires a , and bearing upon all sections of the supports a^9 with equal pressure, are metal 55 housings a^3 . Secured to these housings and locking the latter and the sheaths $a' a^2$ together, are frames a^4 , Fig. 8, also disposed transversely of the wires a and bearing with equal pressure upon all cross-sections of the 60 housings a^3 . Said frames a^4 are provided 65

with pin-bearings a^5 , two upon each frame, the bearings upon the frame at one end of the electro-thermic element being disposed at right angles to those upon the frame at the other end. As a result of this construction of the electro-thermic element, I have provided a plurality of conductor members in series, which exert a pull upon their supports individually, simultaneously, and collectively, when the supports are normally suspended in operative position, the wires adjusting themselves, both during the making and during the operation of the element, within the deep grooves a^{10} which keep the separate wires apart. The relative right-angular arrangement of the bearings at the two ends of the element, together with the equal pressure produced upon all sections of the wires a by the housings a^3 and the frames a^4 , effect an equal tension in the individual wires. Further, by reason of the relative right-angular arrangement of the pin-bearings a^5 , the electro-thermic element can, when in operative position, oscillate in both vertical and horizontal planes. 70 75 80 85 90

I wish to call particular attention to the fact that flexure of the supports a^9 is obviated by means of the construction hereinbefore described, so that they cannot be strained out of shape or position by the tension in the wires a ; and, also, to the fact that, due to the great sub-division of the wires, they heat and cool rapidly, and thus enable the needle to respond to and indicate any changes in the current very quickly. It is therefore seen that when the conductor members a are contracted or expanded, the effect of each such conductor member upon the supports is simultaneous, the total result being the collective effect of all the members, each member acting at the same tension. Since the tensile strength of the element A is equal to the sum of the tensile strengths of all the wires a , it is evident that the full thermic effect of the current may be obtained and expressed in force, the output of power being limited only by the limit of elasticity of the wires a . This amount of power is so much in excess of that needed for indicating mechanism that I am enabled to reduce both the tension of the wire elements and the heat of expansion far below the safe limits to be observed in order to prevent deterioration and still obtain more than sufficient force to easily operate the said indicating means. This, of course, depends upon the number and length of wires a . In practice I make this number such as to give a desired predetermined resistance. This should be such as to cause the conductor to transmit a current of about one-tenth of an ampere. The free ends of the conductor are wound to form terminals $a^6 a^6$ connected to the binding posts N, Fig. 1, each comprising several strands of wire, one terminal at 95 100 105 110 115 120 125 130

each end of the element A, as shown, Figs. 10 and 11, or any other suitable or desirable arrangement. The strands entering into the respective terminals a^6 being thus wound together and clamped, along with the intermediate turns or convolutions of wire, between the two corresponding insulating sheaths by means of the metal housing a^2 , are in effect secured to the support and thus form fixed points of attachment for said wires to the latter. In other words, the terminals a^6 are not under tension but being loose may be made of any suitable length so as to permit of their ready connection with binding posts N. It will accordingly be seen, that, as stated above, the electro-thermal element A may be easily detached and bodily removed, all without disarrangement of the strands upon the supports about which they are wound.

Referring now particularly to Figs. 1, 2, 3, 4, 14 and 15, B represents a compensatory thermic element not forming a part of the electric circuit, which is hence expanded and contracted only by changes of temperature in its environment, it being provided with a central pin bearing b on its right hand support b^{11} , and two pin-bearings b' upon its left hand support, Fig. 15. Hence, a change in one of the elements A and B, due to changes of temperature of the atmosphere or of the parts, is compensated for by a like change in the other element, so that the indicating mechanism is actuated only by means of the thermic effect of the current upon the wires of the electro-thermic element A. A strong spring-plate C is secured in the case D of the voltmeter by means of a bolt E, said spring-plate C passing around a steadyng bolt E' and being provided at its outer end with insulated pin-bearings c. This spring-plate C is an adjuster of tension, equalizing the tension of the two elements A and B whenever either of them is affected by the heat. An oscillatory plate F, Figs. 1, 2, 4, 6, and 7, is provided with conical recesses f centrally-located relatively to the elements A and B and adapted to receive the pin-bearings c where-
50 by said plate F is fulcrumed upon said pin-bearings, said recesses being the dotted middle ones of the upper and lower sets of three, shown in Fig. 6. One end of the electro-thermic element A and one end of the ther-
55 mic element B are pivoted upon said oscillatory plate F and at equal distances from the pin-bearings c, the relative position of the elements A and B and the oscillatory plate F being fully shown in the drawing. Since
60 the distance from the pin-bearing c to the pin-bearing b' is exactly equal to the distance from the pin-bearing c to the pin-bearing a^5 , and since the elements A and B are of the same material, the expansion or con-
65 traction due to external heat will not affect

the zero point. Said oscillatory plate F is also provided with conical recesses f f for the pin-bearings b' and a^5 , as shown in Fig. 6, the left recesses f shown in said figure being adapted to receive the pin bearings b' , 70 and the right recesses f being adapted to receive the pin bearings a^5 , but obviously the pin-bearings in either or all cases might be secured to the oscillatory plate F and the conical recesses be provided in the spring-plate C, thermic element B, and electro-thermic element A, respectively. Suitably supported upon an annular member H of the frame is a second member H', Fig. 1, having its inner end located substantially in the axial line of the instrument, in which end is mounted an arbor h upon which is carried an indicating needle h', Figs. 1 and 2. The arbor h is provided with two flanges h^2 which form between them a drum h^3 . 80 The indicating needle h' rests upon the upper flange h^2 and is clamped from above by a washer h^4 . Adjustably secured to the oscillatory plate F by means of a clamp j^{11} is a lever or fork J provided with flexible tines j , the extremities of which are designed to be widely separated and connected by a thread or belt j' which is wrapped about the drum h^3 of the pointer h'. The belt or thread j' is of such a length that a great latitude of flexure is secured, so that the friction upon the drum h^3 , which would be caused by the movement of the tines j in adjusting the lever J, is greatly reduced. By reason of the adjustment of the lever, the range of movement of the needle can be regulated, so that it is not necessary to provide a separate scale for each instrument, but the latter can be adjusted to any predetermined scale within reasonable limits. It will thus be noted that any expansive effects of the wire a , due to the passage of an electric current, will set the spring C into operation to equalize the disturbed tension of the two members A and B and thus communicate a movement to the oscillatory plate F, which will in turn cause the actuation of the pointer h', thus definitely indicating the movement upon the dial. 100

In order to adapt the instrument for use as an ammeter, either one of two expedients may be adopted: (1) utilizing a heavy conductor sufficient to carry a current of the specified strength, such conductor having a small resistance like silver, and winding it serially upon insulating supports; or, (2) winding a coil of thin wire of great resistance in parallel by stringing it upon metal supports, thus producing a flat coil parallel wound. By thus discarding the insulation in the sheaths or supports the conductor elements or wires a are taken out of series and put into parallel, and the resistance of the whole element is reduced proportionately to the whole number of wires and inversely as

- the length of the wires so paralleled, so that the instrument is adapted to measure current strength or amperes. To make this ammeter form of construction, the wires α are soldered or otherwise suitably secured to the wings α^8 of the supports α^7 , Figs. 12 and 13, in order to make a perfect contact. The pin-bearings α^5 of these supports α^7 are not designed to project beyond these wings α^8 .
- 5 It will also be noted in the volt-meter construction, Figs. 10 and 11, that the pin-bearings α^5 do not project beyond the metal housings α^3 , but, in fact, are so short that their pivot points are drawn slightly within the 10 outer extremities of said housings, whereby the supports cannot turn upon themselves as they would if the pin-bearings were too long; while, on the other hand, such bearings are of a sufficient length so that there is 15 no error introduced into the reading by reason of the expansive effects of the supports, but only the expansive effects of that part of the wires between the inner ends of the pin-bearings affects the operation of the needle.
- 20 Referring to Figs. 1 and 3, it will be noted that the right-hand end of the thermic element B is pivoted to a plate L and the right-hand end of the electro-thermic element A is pivoted to a second plate K on 25 both sides of an opening k provided in said plate. Both of said plates K and L are secured intermediately of the base-member D and the annular member H by means of the bolts P and Q respectively, the plate K being 30 rigidly secured by the bolt P and the lugs k^2 , and the plate L having a turning movement upon the bolt Q. Said plates K and L are secured together by means of the bolt S which is longitudinally fixed relatively to 35 the frame of the appliance and relatively to the plate K, but which has a screw-thread engagement with the inner end of the plate L, so that the distance between the latter and said plate K can be adjusted, whereby the 40 zero point can be obtained by turning the bolt S as desired and moving the inner end of the plate L in or out, said plate turning upon the bolt Q.
- 45 Referring particularly to Fig. 15, I have provided an element of a construction where-in one of the conductor-supports has two bearings disposed in line with the longitudinal axis of said support; whereas, the support at the other end has only one bearing disposed centrally of the latter support, whereby the conductor-ribbon or wires are rendered self-adjusting as to tension, when the element is in operative position. Suitable terminals for the appliance are indicated at T T', Fig. 1. All appreciable errors of reading, due to induction in potential or volt-meter coils, are eliminated by having the opposing wires α in close approach so as to render them non-inductive, 50 as shown particularly in Figs. 9 and 10. To

indicate how negligible is the induction in these coils due to alternating currents, I herewith give data of a voltmeter coil designed to measure 150 volts:

Width of spool winding in centimeters.....	1.9	70
Cross-sectional area of the coil in square centimeters.....	2.02	
Number of turns of wire.....	48	
Resistance of the wire.....	1500 ohms	
Turns of wire per centimeter of width.....	25.3	

150 volts, direct current, will force $\frac{1}{10}$ of an ampere through the 1500 ohms resistance. Assuming the frequency of an alternating current at 100, a pressure of

$$\sqrt{(150)^2 + (.00194)^2}$$

volts would be required to force $\frac{1}{10}$ of an ampere through this same resistance of 1500 ohms, on an alternating current circuit, where

$$2\pi fI = .0194 \text{ ohms.}$$

Then, since

$$C = \frac{E}{\sqrt{R^2 + (2\pi fI)^2}},$$

E=150.000000125 volts, which is so slight a difference from the voltage of the direct current as to be beyond the mechanical limits of measurement.

Having thus described my invention in detail, that which I particularly point out and distinctly claim, is:—

1. In electro-metric appliances, an independent, bodily-removable hot-wire element comprising supports, and a continuous conductor wound about said supports and having its respective ends fixed thereto.

2. In electro-metric appliances, an independent, bodily-removable hot-wire element comprising two supports each provided with grooves extending transversely of its axis throughout its length, and a continuous conductor wound about said supports and lying in the grooves therein, the respective ends of said conductor being fixed to said supports.

3. In electro-metric appliances, a detachable hot-wire element comprising a plurality of wires; two supports provided with grooves in which said wires are wound, opposing wires being disposed in close approach; insulating sheaths adapted to inclose the respective supports; and metal housings for said sheaths.

4. In electro-metric appliances, a hot-wire element comprising a plurality of wires; two supports provided with grooves in which said wires are wound; insulating sheaths adapted to inclose the respective supports; metal housings for said sheaths; and frames adapted to lock said sheaths and housings together.

5. In electro-metric appliances, a hot-wire element comprising a plurality of wires; and supports, upon which the latter are se-

- rially wound, each comprising two insulating sheaths adapted to receive and inclose the wires, and a metal housing adapted to lock said sheaths together.
5. In electro-metric appliances, a detachable hot-wire element comprising a plurality of wires; and supports, upon which the wires are serially wound, each consisting of two insulating sheaths adapted to receive and inclose the wires, a metal housing adapted to lock said sheaths together, and a frame adapted to lock said sheaths and housing together.
10. In electro-metric appliances, a hot-wire element comprising a plurality of wires; and supports, upon which the latter are serially wound, each provided with two insulating sheaths adapted to receive and inclose the wires, and bearings, the bearings of one support being arranged at right angles to the bearings of the other support.
15. In electro-metric appliances, a detachable hot-wire element comprising a plurality of wires; and supports upon which the latter are serially wound, each consisting of two insulating sheaths adapted to receive and inclose the wires, a metal housing for said sheaths, and a frame provided with bearings and adapted to lock said sheaths and housing together, the bearings of the frame of one support being arranged at right angles to the bearings of the frame of the other support.
20. In electro-metric appliances, a hot-wire element comprising a plurality of wires; and supports for the latter consisting of a divided bobbin upon which said wires are wound, and two sets of pin-bearings fixed relatively to the respective parts of said bobbin, said two sets of bearings being arranged at right angles to one another.
25. In electro-metric appliances, a detachable hot-wire element comprising a plurality of wires; and supports for the latter consisting of an insulating divided bobbin upon which said wires are serially wound, and members inclosing the respective parts of said bobbin and provided with pin-bearings, the bearings of one of said members being arranged at right angles to the bearings of the other members.
30. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
35. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
40. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
45. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
50. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
55. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
60. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
65. In electro-metric appliances, a hot-wire element comprising a plurality of wires; and supports for the latter consisting of a divided bobbin upon which said wires are serially wound, and bearing with equal force upon all cross-sections of said bobbin, said members being provided with pin-bearings, and being adapted to lock said sheaths and housing together, the bearings of the member of one support being arranged at right angles to the bearings of the member of the other support.
70. In electro-metric appliances, a detachable hot-wire element comprising a plurality of wires; and supports for the latter consisting of an insulating divided bobbin upon which said wires are serially wound, insulating sheaths adapted to inclose the respective parts of said bobbin, metal housings tightly inclosing said sheaths transversely of said wires and bearing with equal force upon all cross-sections of said bobbin, and frames adapted to lock said bobbin, sheaths and housings together, and provided with pin-bearings, the bearings of one of said frames being arranged at right angles to the bearings of the other frame.
75. In electro-metric appliances, a hot-wire element comprising a continuous conductor wound into a flat coil, and insulating oscillatory supports over which said conductor is so wound, changes in the tension of each individual strand of wire being adapted to automatically oscillate said supports.
80. In electro-metric appliances, a detachable hot-wire element comprising a conductor, and supports for the latter each provided with bearings and including a part of a divided bobbin, the bearings of one support being arranged at right angles to the bearings of the other support.
85. In electro-metric appliances, a hot-wire element comprising a single metal ribbon or wire, and supports for the latter each provided with pin-bearings and comprising a part of a divided bobbin, the bearings of one support being arranged at right angles to the bearings of the other support.
90. In electro-metric appliances, a hot-wire element comprising a conductor, and supports for the latter each provided with bearings and including a part of a divided bobbin, the bearings of one support being arranged at right angles to the bearings of the other support.
95. In electro-metric appliances, a hot-wire element comprising a single metal ribbon or wire, and supports for the latter each provided with pin-bearings and comprising a part of a divided bobbin, the bearings of one support being arranged at right angles to the bearings of the other support.
100. In electro-metric appliances, a hot-wire element comprising a conductor, and supports for the latter each provided with bearings and including a part of a divided bobbin, the bearings of one support being arranged at right angles to the bearings of the other support.
105. In electro-metric appliances, a spring-plate provided with insulated bearings, a second plate adapted to oscillate upon said bearings, the spring tension of said first plate being exerted against said second plate; two members; and bearings pivotally connecting said two members to said second plate, one of said members including an electro-thermic element.
110. In electro-metric appliances, a spring-plate provided with insulated bearings, a second plate adapted to oscillate upon said bearings, the spring tension of said first plate being exerted against said second plate; two members; and bearings pivotally connecting said two members to said second plate, one of said members including an electro-thermic element.
115. In electro-metric appliances, a spring-plate provided with insulated bearings, a second plate adapted to oscillate upon said bearings, the spring tension of said first plate being exerted against said second plate; two members; and bearings pivotally connecting said two members to said second plate; and an electro-thermic element secured to one of said members; the other of said members being subject only to temperature changes.
120. In electro-metric appliances, a spring-plate provided with bearings; a second plate adapted to oscillate upon said bearings; two members; and bearings pivotally connecting said two members to said second plate, one of said members including an electro-thermic element; indicating mechanism and a
125. In electro-metric appliances, a spring-plate provided with bearings; a second plate adapted to oscillate upon said bearings; two members; and bearings pivotally connecting said two members to said second plate, one of said members including an electro-thermic element; indicating mechanism and a
130. In electro-metric appliances, a spring-plate provided with bearings; a second plate adapted to oscillate upon said bearings; two members; and bearings pivotally connecting said two members to said second plate, one of said members including an electro-thermic element; indicating mechanism and a

flexible lever member adapted to actuate the indicating mechanism and adjustably secured to said oscillatory plate.

19. In electro-metric appliances, a spring-
5 plate provided with insulated bearings; a second plate adapted to oscillate upon said bearings; an electro-thermic element pivotally secured to said second plate; a thermic element pivotally secured to said second plate; a fork adjustably secured to said oscillatory plate and provided with yielding tines; an operating needle pivotally secured to the frame of the appliance; and a thread connected to the tines of said fork, passing
10 around the drum of said needle, and of a length such as to allow, when said fork is adjusted, great latitude of flexure without frictional strain upon said drum.

20. In electro-metric appliances, a spring-
20 plate provided with bearings; a second plate adapted to oscillate upon said bearings; two members; pin-bearings pivotally connecting said two members to said second plate; a hot-wire element secured to one of said members, the other of said members being subject only to temperature changes, indicating mechanism; and a flexible lever adapted to actuate said indicating mechanism and adjustably secured to said oscillatory plate.

21. In electro-metric appliances, the combination of a spring-plate and a rigid plate; indicating mechanism; a third plate oscillatorily secured to said spring-plate, and connected to the indicating mechanism; and a hot-wire element and a thermic element both pivotally secured at one end to said rigid plate, and at the other end to said oscillatory plate.

40 22. In electro-metric appliances, the combination of a spring-plate and a rigid plate; indicating mechanism; a third plate oscillatorily secured to said spring-plate, and connected to the indicating mechanism; and a hot-wire element and a thermic element both pivotally secured at one end to said rigid plate, and at the other end to said oscillatory plate, the pivotal points at one end of said hot-wire element being arranged at
45 right-angles to those at the other end.

23. In electro-metric appliances, the combination of a spring-plate and a rigid plate; indicating mechanism; a third plate oscillatorily secured to said spring-plate; a hot-
50 wire element and a thermic element both

pivotal secured at one end to said rigid plate, and at the other end to said oscillatory plate; and a flexible lever adapted to actuate the indicating mechanism and secured to said oscillatory plate.

24. In electro-thermic appliances, the combination of a spring-plate and a rigid plate; indicating mechanism; a third plate oscillatorily secured to said spring-plate; a hot-wire element and a thermic element both pivotally secured at one end to said rigid plate, and at the other end to said oscillatory plate, the pivotal points at one end of said hot-wire element being arranged at right angles to those at the other end; and a flexible lever adapted to actuate the indicating mechanism and adjustably secured to said oscillatory plate.

25. In electro-metric appliances, the combination of a spring-plate and a rigid plate; 75 a third plate oscillatorily secured to said spring-plate; a hot-wire element and a thermic element both pivotally secured at one end to said fixed plate, and at the other end to said oscillatory plate; a fork adjustably 80 secured to the latter and provided with yielding tines; an operating needle pivotally secured to the frame of the appliance; and a thread connected to the tines of said fork, passing around the drum of said needle, and 85 of a length such as to allow, when said fork is adjusted, great latitude of flexure without frictional strain upon said drum.

26. In electro-metric appliances, the combination of a hot-wire element and a thermic element; a plate, connected to the indicating mechanism, upon which one end of each of said elements is pivoted; a spring-plate upon which said first-named plate is fulcrumed; a member rigidly secured to the frame of the appliance, and upon which the other end of said hot-wire element is pivoted; a second member, rotatably secured at one end in the frame of the appliance, upon which the other end of said thermic element 100 is pivoted; and a bolt longitudinally secured to said rigid member and having a screw-thread engagement with the other end of said rotatable member.

Signed by me this 11th day of April, 1906. 105

WILLIAM JANDUS.
